UNITED STATES PATENT OFFICE.

JOHAN DIDRIK HOLSCHER, OF NÖRREGADE, RÖDBY, AND JOHANNES HÖIMARK, OF COPENHAGEN, DENMARK.

BENZENE-HEATED STOVE.

1,367,476.

Specification of Letters Patent.

Patented Feb. 1, 1921.

Application filed November 9, 1917. Serial No. 201,068.

To all whom it may concern:

Be it known that we, JOHAN DIDRIK HOLSCHER, tinker, and JOHANNES HÖIMARK, wholesale merchant, citizens of the Kingdom 5 of Denmark, residing at Nörregade, Rödby, Denmark, and Vesterbrogade, 39, Copenhagen, Denmark, respectively, have invented certain new and useful Improvements in Benzene-Heated Stoves, of which the following is a specification.

The present invention relates to improvements in stoves, employing benzene or the like for fuel.

An important object of the invention is to 15 provide means to properly vaporize the benzene, and mix the same with air, such mixture being supplied to the burner.

A further object of the invention is to provide means to cut off the supply of air to 20 the benzene holding receptacle, when the apparatus is not in use.

Other objects and advantages of the invention will be apparent during the course of the following description.

25 In the accompanying drawings, forming a part of this specification, and in which like reference characters are employed to designate like parts throughout the same,

Figure 1 is a central vertical sectional view 30 through a stove embodying our invention, parts being shown in elevation, and

Fig. 2 is an enlarged central vertical sectional view through the burner.

The stove comprises a stationary lower 35 casing *a*, and an upper casing *b*, which is normally vertical. The casing *b* is hinged to the casing *a*, at *c*. A latch *d* normally serves to retain the casing *b* in the vertical closed position.

40 The upper casing *b* has two horizontal plates *e* and *f* which hold in place a tubular combustion chamber *g*, and prevent the circulation of air between the same.

Arranged within the lower casing *a*, is a 45 fuel receptacle *h*, having a vertical pivoted tube *i* rotatably mounted therein. This tube *i* has its upper end rotatably fitting within a burner tube *j*, receiving the lower end of a burner *k*, provided at its top with an arch of wire gauze *l*, as shown.

50 Arranged vertically within the fuel holding receptacle *h* is an outer tube *m*, having a larger diameter than the tube *i*, and provided at its lower end with a reduced portion in which the lower 55 end of the tube *i* rotatably fits. The reduced

portion of the tube *m* has an aperture *m'* adapted to register with an aperture *l'* in the tube *i*.

Surrounding the upper portion of the tube *i* is a ring *o*, to turn therewith. The ring *o* 60 has an aperture *o'*, adapted for movement into and out of registration with an opening *h'*, in the tube *m*.

The outer tube *m* is provided at its top with a flange *m*^a, engaging a top *p*, having 65 apertures *p'*. The top *p* has a horizontal slot *p''*, receiving a horizontally swinging handle *q*, rigidly secured to the tube *i* to turn it.

The tube *i* is provided in its lower portion 70 with an aperture *r*, and the receptacle *h* is preferably filled with absorbent material *n* for the benzene, in the form of balls of *Agaricus albus* and *Polyporus albus*, powdered and kneaded together with an adhesive.

A distributor *s* of wire gauze is disposed 75 at the lower end of the combustion chamber *g*, and surrounds the burner tube *j*.

The burner *k* is lighted through openings covered by doors *u* and *t*, which doors are 80 connected by a rod *v*, to move together, as shown.

In operation, the benzene is supplied to the absorbent balls within the receptacle *h*. The tube *i* is then turned to bring aperture 85 *o'* into registration with aperture *h'* and aperture *m'* into registration with aperture *l'*. Air is thereby supplied into the upper end of the receptacle *h*, as indicated by the arrow, and the vaporized benzene which is 90 mixed with the air passes through apertures *l'* and *m'*, into the lower end of the tube *i*. In this tube this mixture receives further air through the aperture *r* and the final mixture passes to the burner *k*, and out through the 95 gauze *l*, to be ignited, in the presence of further air passing through the distributor *s*.

By turning the tube *i* the apertures *o'* and *h'*, and *l'* and *m'* are moved out of registration, and the supply of air cut off from the 100 receptacle *h*, and the supply of vaporized benzene cut off from the tube *i*.

Having thus described our invention what we claim is:

A stove of the character described comprising a vertical casing, a tubular combustion chamber extending axially within the casing and spaced therefrom so as to provide an annular chamber between the walls of the combustion chamber and casing, said com- 105 110

burntion chamber and casing walls having alining openings, a horizontal plate fitted in the lower portion of the annular chamber and encircling the lower end of the combustion chamber so as to prevent the entrance of air into and its passage through said annular chamber, a tubular burner projecting into the lower end of the combustion chamber and adapted to be lighted through said 10 registering openings, a pair of doors associated with said openings for closing the

same and connected together to move in unison, a wire gauze distributer arranged at the lower end of the combustion chamber and surrounding the tubular burner to permit 15 the passage of air into said combustion chamber, and means for supplying fuel to the burner.

In testimony whereof we affix our signatures.

JOHAN DIDRIK HOLSCHER.
JOHANNES HÖIMARK.
